(57) **CLAIM**

The ornamental design for a rectilinear exhaust silencer, as shown and described.

DESCRIPTION

FIG. 1 is a front perspective view of a rectilinear exhaust silencer, showing the new design;

FIG. 2 is a bottom perspective view of the rectilinear exhaust silencer of FIG. 1;

FIG. 3 is a bottom view of the rectilinear exhaust silencer of FIG. 1;

FIG. 4 is a top view of the rectilinear exhaust silencer of FIG. 1;

FIG. 5 is a rear view of the rectilinear exhaust silencer of FIG. 1;

FIG. 6 is a front view of the rectilinear exhaust silencer of FIG. 1;

FIG. 7 is a right-side view of the rectilinear exhaust silencer of FIG. 1; and,

FIG. 8 is a left-side view of the rectilinear exhaust silencer of FIG. 1.

The broken lines in the drawings depict portions of the rectilinear exhaust silencer that form no part of the claimed design.
